UNITED STATES PATENT OFFICE

WILLIAM H. WHEELER, OF NEW YORK, N. Y., AND JUDSON C. LOGAN, OF JERSEY CITY,
NEW JERSEY

ANCHORAGE

Application filed February 17, 1927. Serial No. 168,911.

This invention relates to an improved means of anchoring a member to a suitable base in such manner that it cannot be removed without mutilating the member or 5 the base.

The present invention is a modification of the invention covered by Letters Patent of the United States No. 1,568,433, issued January 5th, 1926, and of the invention disclosed 10 in our copending application, Serial No. 168,908 filed February 17th, 1926.

The present invention has for a specific object to provide a form of anchorage for securing an identification plate or device to a 15 panel or board, such as the instrument board or dash board of an automobile. It is customary to make such instrument boards and dashboards of relatively thin sheet metal, which does not provide sufficient body to 20 support a threaded anchorage, such as shown in the aforesaid patent. It is therefore an object of the present invention to provide an anchorage that is particularly adapted for securing an identification device to a relatively thin base or panel.

With these and other objects in view, our invention consists in certain novel features and arrangements and combinations of parts, as will be hereinafter described and pointed 30 out in the claims.

In the accompanying drawings,

Figure 1 is a front elevation of an identification plate secured to a panel;

Fig. 2 is a sectional view taken on the line 35 2-2 of Fig. 1;

Fig. 3 is an end view of one of our anchorage devices;

Fig. 4 is a side elevation, partly broken away, of one of said anchorage devices; and

Fig. 5 is a cross-sectional view showing a 40 modification of our invention.

In Figs. 1 and 2 we have used the numeral 10 to indicate a sheet metal panel, such as the instrument board of an automobile.

45 However the panel need not be of metal, but could, just as well, be of wood or other material. A recess 11 is formed in the panel, and in this recess is fitted an escutcheon 12. The latter may be of any design suitable for

50 the purpose, and is preferably formed with a

marginal bead 13. On the escutcheon and within the bead, is placed the identification plate 14, and the latter is anchored in place by means which will now be described.

Apertures 14' are cut in the recessed portion of the panel and in the escutcheon, to receive a pair of screw plugs 15. Each screw plug is exteriorly threaded at one end and has an annular flange or shoulder 16 near the opposite end. The threaded ends of the screw plugs are passed through the apertures 14' and screwed into threaded openings 17 in a backing plate 18 which bears against the rear face of the panel 10, while the shoulders 16 bear against the front face of the escutcheon. Thus the screw plugs bolt the escutcheon to the panel and are themselves securely affixed to the panel. It will be observed that the backing plate serves as a nut for the screw plugs, but because the nut is engaged by both of the screw plugs simultaneously, it is impossible to unscrew the nut. There is no way of operating from the rear of the panel to disengage the screw plugs from the panel, without cutting the backing plate or the panel. Furthermore, the screw plugs and the backing plate are made of hardened metal which will resist files, saws, or other cutting tools. The only way, then, of removing the screw plugs, is to operate on them from the front of the panel, and this is precluded by covering the front ends of the screw plugs with the identification plate 14, as will be explained presently.

Each screw plug 15 is formed with a recess 19, in its forward or unthreaded end, leaving an annular rim 20 which projects beyond the shoulder 16. The recess 19 is undercut to form an inwardly projecting lip 21 at the mouth of the recess, and this lip has a sharp lower corner 22 and a rounded upper corner 23. A slot 24 is cut through opposite sides of the rim, to receive a screwdriver or other tool, whereby the screw plug may be screwed into the backing plate. Each opening 17 in the backing plate, is made of a size to provide a very tight fit for the threaded end of the screw plug, so that the latter cannot work loose.

Within the recess 19 is placed an expander

plug 25, which has a cylindrical body 26 with a base flange 27 at the inner end and a frusto-conical portion 28 at the outer end. The base flange is of such size that only by the expenditure of considerable pressure may the expander plug be forced past the lip 21 into the recess, and once introduced into the recess, the expander plug will be retained therein, although it will have considerable freedom of motion within the recess.

10 The plate 14 is provided with a pair of annular flanges 29, adapted to enter the screw plugs 15 between the lips 21 and the expander plugs 25. The flanges 29 are formed on the 15 under side of the plate, on centers spaced to align with the centers of the apertures 14'. Each flange 29 is formed between a central bore 30 and an exterior, concentric groove 31. Neither the bore nor the groove break through 20 the outer or front face of the plate. The bore 30 is deep enough to receive the expander plug 25, when the plate 14 is pressed home against the escutcheon 12, and is of a diameter somewhat smaller than the diameter of 25 the cylindrical body 26. The groove 31 is adapted to receive the rim 20, and has a countersunk portion 32 at the mouth thereof, to receive the shoulder 16. The groove 31 extends to within a short distance of the outer face of 30 the plate 14, thereby providing an area of weakness 33 surrounding the flange 30.

After the screw plugs, with expander plugs retained therein, have been secured to the panel in the manner described above, 35 the plate 14 is anchored to the panel by forcing the flanges 29 into the recesses 19. The rounded corners 23 assist in introducing the flanges into the mouths of the recesses. As the flanges are forced in, they 40 follow the contour of the expander plugs, being flared out by the frusto-conical portions 28 into the undercut portion of the recesses and then hugging the cylindrical portions 26. Any effort to withdraw the plate 14 from its 45 seat, is resisted by the sharp corners 22, which dig into the flared portion of the flanges 29, and the parts are so proportioned that the weakened area 33 will tear out before the flanges will shear off. The flanges 29 adhere 50 by friction to the cylindrical portion 26 of the expander plugs, and the latter, since they are not secured to the screw plugs, tend to rise with the flanges 29, when any effort is made to withdraw the plate from its anchorage, there- 55 by jamming the flanges 29 against the corners 22 and preventing said flanges from being contracted and drawn out by the same path they entered the recesses 19. Thus a firm anchorage for the plate 14 is provided, which 60 will tear a piece out of the plate before it will let go.

As stated above, the screw plugs 15 and the backing plate 18 are made of highly hardened metal, and if heat be applied, sufficient to 65 draw their temper, it will disfigure the outer

surface of the plate 14. The backing plate is relatively thick and has a large capacity for heat, hence a great deal of heat will be required to draw its temper.

Attention is called to the fact that the plate 14 is relatively thicker than that shown in the aforesaid Patent (No. 1,568,433), providing sufficient metal to form the flanges 29 of adequate length for anchorage purposes without having them project from the rear face of the plate. This reduces the cost of manufacture and permits the plate 14 to seat firmly against the escutcheon. The latter, aside from providing an ornamental border or frame, also prevents the introduction of a tool under the plate to pry it off its seat.

As in the construction shown in the aforesaid patent, the rims 20 of the screw plugs, project so far into the plate 14, that it is impossible to saw the plate edgewise, clear of 85 said rims, without tearing or breaking through the outer face of the plate.

Fig. 5 shows a plate 14 mounted on a base 10' of slightly different form from the base shown in Figs. 1 and 2. The base 10' has no recess therein. An escutcheon plate 12' provided with a marginal bead 13' bears directly against the face of the base. Otherwise the construction is similar in every respect to that shown in Figs. 1 to 4, inclusive. 95

We claim:

1. In an anchorage of the character described, a base formed with two apertures, a plate on one side of the base, a pair of screw plugs covered by and affixed to the plate and projecting through said apertures respectively, and, on the other side of the base, a nut common to both of said plugs and into which said plugs are screwed. 100

2. In an anchorage of the character described, a base formed with two apertures, a plate on the forward side of the base, a pair of screw plugs secured to the plate and projecting through said apertures respectively, each of said plugs being formed with a shoulder bearing against the forward side of the base, and a nut at the rear side of the base into which said plugs are both screwed. 110

3. In an anchorage of the character described, a base formed with two apertures, a plate on the forward side of the base, a pair of screw plugs secured to the plate and projecting through said apertures respectively, each of said plugs being formed with a shoulder bearing against the forward side of the base, the plate being recessed to receive said shoulders, and a nut at the rear side of the base into which said plugs are both screwed. 115

4. In an anchorage of the character described, a base formed with a recess and having a pair of apertures in the recess penetrating the base, a plate seated in the recess, a backing member on the opposite side of the base, and a pair of screw plugs covered by 120 130

and affixed to the plate, said screw plugs projecting through said apertures and being screwed into said backing member.

5. In an anchorage of the character described, a base, screw plugs passing through said base and having shouldered heads bearing against the front face of the base, a backing plate bolted to the rear of said base by means of said screw plugs, a plate seated against the front face of the base and recessed to receive said shouldered heads, each screw plug having an undercut recess in the head thereof, the plate being formed with flanges adapted respectively to enter the recesses in the screw plugs, and means for offsetting the flanges into the undercut portions of the recesses in the screw plugs.

6. In an anchorage of the character described, a base formed with a pair of apertures, a plate on one side of the base covering said apertures, a screw plug affixed to the plate and projecting through one of said apertures, a nut on the other side of the base into which the plug is screwed, and means 25 extending through the other aperture, said means engaging the nut and the plate to prevent turning of the nut or the plate.

7. In an anchorage of the character described, a base formed with a pair of apertures, a plate on one side of the base covering said apertures, a screw plug affixed to the plate and projecting through one of said apertures, a nut on the other side of the base into which the plug is screwed, and means 35 secured to the plate and extending through the other aperture, said means engaging the nut to prevent the nut from being turned.
